UNITED STATES PATENT OFFICE

94,901

DESIGN FOR A GAME BOARD

Herbert E. Jackman, Rochester, N. Y.

Application December 11, 1934, Serial No. 54,389

Term of patent 14 years

To all whom it may concern:

Be it known that I, Herbert E. Jackman, a citizen of the United States, residing at Rochester, in the county of Monroe and State of New York, have invented a new, original, and ornamental Design for a Game Board of which the following is a specification, reference being had to the accompanying drawing, forming part thereof.

In the drawing:

The figure is a plan view of a game board, showing my new design.

The article shown has no appreciable thickness.

I claim:

The ornamental design for a game board, as shown and described.

HERBERT E. JACKMAN.
